AUTOMATIC LINER SAFETY

B. A. Mills, Shreveport, La.

Application August 21, 1933, Serial No. 686,119

4 Claims. (Cl. 199—52)

The present invention relates to an attachable safety locking device for use in slug and type-casting machines to prevent mold liners from destruction prematurely by force of ejector blades, 5 when same is left out of corresponding adjustment through error or neglect while attempting to operate said slug and type-casting machines.

This device fastens to the left hand assembler elevator gib, ejector dial lever, right hand vise 10 jaw plate screw, vise locking screws and the mold turning pinion, comprising locking and unlocking means which move an obstruction into and out of the path of the assembler elevator automatically. In eliminating mold liner damages, this device subsequently puts an end to many other resultant mechanical disturbances experienced by 15 operators when mold liners are broken by force of moveable members of said slug and typecasting machines.

Drawings

Figures 1, 2 and 4 are respectively perspective views of assembler elevator, vise mechanism and 20 ejector shifter mechanism of slug and type-casting machines; also portions of the safety attachments constructed and arranged in accordance with the present automatic liner safety.

Fig. 3 is a detail interior view of an extension pivot pin diagrammatically arranged for showing 30 an aperture longitudinally extending through walls of its tubular section, a coil spring situated therein which is operatively connected with moveable members of its adjustable receiver cap; a stop pin rigidly secured in front end of said tubular portion, also an interchangeable extension collar 31.

Fig. 5 is an edge view of the intermediate latch lever mechanism diagrammatically arranged for 40 showing portions of interchangeable bracket 15 and an intermediate latch lever 3, also holding means which moveably receive same.

Fig. 6 is a detail elevational rear view of the major unit of this device diagrammatically arranged for showing a dial lever attachable bar 45 34, a governor mechanism having springs and adjustable members which move a cam 35 into and out of the path of segments contained in a dial lever attachable bar; a frame 42 having a small aperture in throat of clearance E, and an intermediate bracket 50 constructed to moveably receive a coil spring 44 and an intermediate bracket pin 51 which extends through front and back ends of frame 42 and intermediate bracket 50; an intermediate bracket pin spring 43 situated 50 so as to bring aperture in throat of the clearance in underside of frame into engagement with top of front end of intermediate bracket upon its forward movement; a cam connecting rod 38; an elastic spring 39 and means set forth in the following detail description.

Description

Attention is drawn to the fact that in said slug and type-casting machines is contained an assembler elevator indicated at R Fig. 1, which is operatively connected with a long finger and delivery slide mechanism Q Fig. 1. The said long finger and delivery slide mechanism has a lower end starting roller which engages a starting clutch, located on the main cams of said slug and type-casting machines. The said cams are caused to rotate when said starting clutch is engaged by said starting roller, as the upper end of the long finger is released by upward movement of said assembler elevator R Fig. 1, and moved by finger Q Fig. 1, of the transfer slide which slides the matrices through the intermediate channel indicated at 33, Fig. 1.

Secured rigidly to the assembler elevator gib X, Fig. 1, is an interchangeable bracket 15. Said bracket is provided with stop screws 25 and 26, Fig. 1, adapted to moveably receive intermediate latch lever 3 by means of bolt 24 and adjustable means 1 and 27, Fig. 5; being also adapted to rigidly receive an elastic spring 39, Fig. 6, and an intermediate bracket 50, Fig. 6. The said intermediate latch lever 3, has adjustably mounted on its upper left portion set screws Z, which provide holding means for a buffer plate 2, which is constructed with right and left shoulders indicated at A and B, also a slot in clearance in its lower portion, adapted to admit its adjustments.

The intermediate bracket 50, Fig. 6, has moveably mounted on its upper front and back ends, a governor mechanism which comprises a front 35 cover plate 49, Fig. 6, a cover plate assembler elevator buffer 41, and an adjustable back pawl 40, which is secured in position by screws H, Fig. 6, and an interposing coil spring operatively connected with the front end of said intermediate 40 bracket and back end of said frame, which is adapted to rigidly contain said intermediate bracket pin. The said pin being adapted to pass through said intermediate bracket pin spring 44, Fig. 6, comprising means which impart alternating motion between assembler elevator as indicated at A, Fig. 6, and dial lever attachable bar as indicated at D, whenever pawl C of cam 35 is moved to obstructing position by backward motion of lug 45, indicated at F, Fig. 6, after said 50 governing mechanism is brought into engagement with upward movement of said assembler elevator at A, Fig. 6; after intermediate latch lever 3 is withdrawn from obstructing position at SS, by upward motion of dial lever key 6; said 55 upward motion having caused pawl C to recede to its non-obstructing position by action of an elastic spring indicated at 39, Fig. 6, which now permits the dial lever to be moved without interference to whatever position desired.

The said cover plate assembler elevator buffer 41, Fig. 6, having now been latched by spring 51, which draws clearance in throat of frame 42, over top of front end of intermediate bracket 50, 5 at E, Fig. 6, remains in obstructing position and will unlatch automatically when engaged by upward movement of said assembler elevator R as indicated at A, Fig. 6; which operation throws said pawl C of cam 35 back into obstructing 10 position, or operative position with said dial lever attachable bar 34, at D.

When the vise mechanism W, Figs. 1 and 2, is 15 opened for making changes of mold liners, its outward motion brings curved end of trigger 4 into engagement with shoulder B of buffer plate 2 causing opposite end of said intermediate latch lever 3 to rise to obstructing position S, Fig. 1.

The intermediate latch lever 3 is held in elevated position by means of a compression spring 20 1, Fig. 5, and may be lowered to inactive position by unlocking means adapted to the linotype class of slug and type-casting machines as provided at 6, Fig. 1; or unlocking means adapted to the intertype class of slug and type-casting machines 25 as provided in an auxiliary unlocking arrangement as indicated at 8 and 19, Fig. 4; also 8 and D, Fig. 1.

Interchangeable bracket 15 of the type indicated at Y, Fig. 5, and 15, Fig. 4, is provided to 30 adjustably receive an angle bar 8 by holding means 20 and 22 at F, Fig. 4; same also being adapted to support adjustable lug 19.

Stop screws 25 and 26, Fig. 1, are situated in the upper portion of said interchangeable bracket 35 15, being provided to receive an intermediate bracket 50, and to arrest the activity of the intermediate latch lever 3 when moved to active or inactive position.

The extension pivot pin 14, Fig. 3, is constructed 40 with a tubular portion with a stop screw 29 situated near the entrance thereof provided to accommodate and to hold in position an interposing coil spring, which is also situated in said tubular portion, being provided to reciprocally 45 move a receiver cap 12 alternately with each movement of mold turning pinion 32, Fig. 2. An aperture in walls of said tubular portion, extends from stop screw 29 to N, provided to accommodate pin 17, in collar 13 of receiver cap 12, Figs. 50 2 and 3.

Collar 31, Fig. 3, is provided to be used as an extension between collar 13 and mold turning pinion 32, whenever desired. Collar 13, Fig. 3, contains projecting helical ribs or threads on its 55 exterior portions corresponding with those contained in interior portions of receiver cap 12, adapted to adjustably receive and adjust same in accordance with whatever variations may be found in the different models of said slug and type-casting machines. The said pin 17, which extends through end of collar 13, is provided to move said receiver cap alternately with each inward and outward motion of said mold turning pinion.

65 The two supporting collars 21, Figs. 1 and 2, are constructed so as to be attachable to vise locking screws U and to be operatively connected with vise mechanism W, at H, being adapted to support throat pieces 11. Said throat pieces are 70 constructed so as to operatively receive a reciprocal register rod 28, Figs. 1 and 2, as indicated at H lugs 5, being also adapted to accommodate other types of reciprocal register rods not here shown but indicated at P, Figs. 1 and 2.

75 Register plate O, Fig. 2, is constructed so as

to be attached to the under side of left hand throat piece 11, Fig. 2, having a tail piece 7 provided to accommodate a register plate spring 23, being adapted to control and register the activity of buffer T, of said reciprocal register rod with said receiver cap 12, Fig. 2.

The reciprocal register rod 28, Figs. 1 and 2, is comprised of a moveable member having angles which permit it to pass operatively from said receiver cap 12, through register plate O, and throat pieces 11 at 5, to right shoulder A of buffer plate 2, Fig. 1, being adapted to slideably engage said shoulder, imparting a downward stroke which causes the opposite end of said channel latch to move into the path of said assembler elevator at S, Fig. 1. This obstruction prevents operation of the said slug and type-casting machines while improperly adjusted and no damage of mold liners can be had while it is thus locked in normal position. The function here described 15 however, is caused by any interference that may draw said mold turning pinion outwards sufficient to dislocate the then corresponding mold, or interchange positions of said mold liners; and to move out of engagement with said shoulder A 20 when said mold turning pinion 32 is brought back 25 into normal position.

The unlocking arrangement adapted for use on slug and type-casting machines equipped with ejector dial levers as indicated at I, Figs. 1 and 30 6, is comprised of a dial lever key 6 and holding means which adjustably fastens same to the front side of said dial lever provided as a lug or obstruction, in the path of which stands the lower side of said intermediate latch lever; being adapted 35 to release the assembler elevator R, Figs. 1 and 6, at S, when upon its upward movement said key is brought into engagement with the said intermediate latch lever 3 at V, Fig. 1, as the said dial lever reaches its full distance upwards. 40

The auxiliary unlocking arrangements adapted for use on slug and type-casting machines equipped with ejector shifter, as indicated at L and M, and 30, Fig. 4, is comprised of an angle bar 8, Figs. 1 and 4, having mounted on its upper 45 end an auxiliary key, as indicated at D, Fig. 1, and perforations at its lower left angle indicated at F, Fig. 4, same being provided with holding means 20 and 22, which also adjustably holds same to the lower end of said interchangeable 50 bracket 15, Figs. 1, 4, 5 and 6; to the opposite end of which is also attached a lug 19 as indicated at K, which operatively connects it with the under side of an ejector locating lever indicated at M; which must be lowered with the hand 55 whenever a non-corresponding change of the ejector may be possible, or a different ejector is desired; but which then can only be done by moving an ejector shifter as indicated at L, Fig. 4. This operation also automatically makes a downward stroke in collar C of said intermediate latch lever 3, Fig. 1, moving same to non-obstructing 60 position and thereby unlocking said assembler elevator R at S, Figs. 1 and 6.

The intermediate latch lever is constructed 65 with a lug 37, Fig. 6, and perforations to accommodate certain stationary and moveable holding means already described and otherwise indicated at I, Figs. 1 and 6; 27, Figs. 1 and 5; 46, 47, 48, 36, 43 and 51, Fig. 6; and a projecting member at SS, Fig. 6; being adapted so as to move into and out of the path of the said assembler elevator automatically.

Mold liners are located or dislocated in the 70 linotype class of slug and type-casting machines 75

by one, of three distinct operations primarily, they are the following:

First.—By unlocking the vise W, Figs. 1 and 2, in which case, curved end of trigger 4 locks 5 said machine and same will only unlock itself automatically when the ejector mechanism previously described is brought within a size which cannot damage said mold liners.

Second.—By revolving the mold liners and 10 mold mechanism which is accomplished by first moving one of its members called mold turning pinion 32, Fig. 2, outward which releases it from a stud pin not shown, and then to any molding position wanted, but in this case, a receiver cap 15 12, Fig. 2, which obstructs lower end of said reciprocal register rod at T, causes its upper end to strike the said intermediate latch lever mechanism at A, Fig. 1, which also locks said machine as first above operation.

Third.—By lowering the dial lever I, Figs. 1 and 20 6, a size of ejector too large to correspond with said mold liner may be brought into position which when attempting to pass, said mold liner would strike and dislocate as well as damage 25 same, but instead, its attachable bar 34, Fig. 6, would engage pawl C of cam 35 and by means of a cam connecting rod 38, said intermediate latch lever 3 locks said machine as in first and 30 second cases above mentioned; each being subject to the same subsequent unlocking operations.

The ejector dial, ejector dial locating lever and the ejector shifter all being in one mechanism or unit form in the intertype class of slug 35 and type-casting machines, the said intermediate bracket 50, its mechanism and the attachable bar mechanism 34, Figs. 1 and 6, are eliminated and in all other respects the principles of manipulations are similar and therefore 40 the safety device operates the same thereon.

The device is self functioning throughout and therefore additional instructions seem unnecessary.

Having thus described the invention I claim:

1. In an automatic liner safety device, adapted to be attached to the assembler elevator gib, vise jaw plate screw, vise locking screws, mold turning pinion and dial lever; an interchangeable bracket located on the left hand lower side 45 of the assembler elevator gib, adapted to support locking and unlocking means; an intermediate bracket located on said interchangeable bracket's upper left hand front side, adapted to support a governing mechanism; a cam located on the inner side of said interchangeable bracket, having a pawl which adapts it to be moved into and out of engagement with a dial lever attachable bar; a cam connecting rod, adapted to reciprocally connect an intermediate 50 latch lever with a cam; a cam spring located on the lower side of said interchangeable bracket and holding means, adapted to move to inoperative position by upward movement of said dial lever; a lug located on right hand end of said frame and holding means, operatively connected with a lug on upper left hand portion of said cam, adapted to move a right hand cam pawl into engagement with said dial lever attachable bar and to perform other necessary 55 functions; a cover plate assembler elevator buffer located at the left hand end on the upper side of said frame and holding means, adapted to move into and out of the path of the assembler elevator which automatically move said cam pawl to its operative position; an adjustable back pawl operatively connected with said frame, adapted to be engaged by upward movement of said cam and to move an obstruction into the path of the assembler elevator; a frame and governing mechanism moveably mounted on said intermediate bracket, adapted to reciprocally govern alternating motions; a front cover plate 10 and holding means; a dial lever attachable bar operatively connected with said dial lever; an intermediate latch lever, operatively connected with the assembler elevator gib, adapted to move into and out of the path of the assembler elevator; a dial lever key, operatively connected with the said dial lever, adapted to withdraw an intermediate latch lever; a buffer plate, operatively connected with the intermediate latch lever, adapted to be engaged by a trigger; a trigger, operatively connected with the right hand vise jaw plate screw, being adapted to moveably engage said buffer plate.
2. In an automatic liner safety device, adapted to be attached to the assembler elevator gib, vise jaw plate screw, vise locking screws, mold turning pinion and dial lever; supporting collars, attachable to the vise locking screws, adapted to support throat pieces; throat pieces, attachable to supporting collars, adapted to support reciprocal register rod mechanisms and means for registering same; a reciprocal register rod, operatively connected with a mold turning pinion, register plate, supporting collars and an intermediate latch lever mechanism, adapted 25 to move an intermediate latch lever to obstructing position when mold turning pinion is interfered with or drawn outward sufficiently to be revolved out of corresponding position with mold liner ejector, and to move out of engagement 30 with intermediate latch lever when mold turning pinion is revolved or seated in operative position and registering means for same.
3. In an automatic liner safety device, adapted to be attached to the assembler elevator gib, vise jaw plate screw, vise locking screws, mold turning pinion and dial lever; an extension pivot pin, operatively connected with a reciprocal register rod and mold turning pinion, adapted to 35 move the reciprocal register rod alternately with each outward movement of mold turning pinion by means of its adjustable receiver cap; an adjustable receiver cap mounted on said extension pivot pin, adapted to adjust same to various models and to reciprocate alternating motions of the mold turning pinion and the reciprocal register rod.
4. In an automatic liner safety device, adapted to be attached to the assembler elevator gib, vise jaw plate screw, vise locking screws, mold turning pinion and dial lever; an angle bar, containing a key at its upper end and an adjustable lug secured adjustably to its lower end, operatively connected with an ejector locating lever, 60 interchangeable supporting bracket and the intermediate latch lever mechanism, adapted to withdraw an intermediate latch lever from obstructing position when its lower end is engaged by the downward movement of the ejector locating lever.
